UNITED STATES PATENT OFFICE.

CHARLES POULAIN, OF PARIS, FRANCE.

COLLAR-SUPPORTER.

1,080,526.

Specification of Letters Patent.

Patented Dec. 2, 1913.

Application filed July 9, 1913. Serial No. 777,992.

To all whom it may concern:

Be it known that I, CHARLES POULAIN, a citizen of the Republic of France, residing at Paris, France, have invented certain new and useful Improvements in Collar-Supporters, of which the following is a full, clear, and exact description.

This invention relates to collar supporters and is designed more particularly to be used in connection with the open style of collars, which curve or flare outward from the neck, in contradistinction to those collars which are substantially straight up and down and hug the neck. The ordinary form of a collar supporter is an elastic strip of some character which tends to hold the collar flat against the neck, but there are various styles of collars, known for instance, as the "Robespierre" or "Medici" which are of varying height and which curve outward from the neck and in which an elastic supporter is impracticable. Therefore, the supporter which I have designed is of pliable or flexible nature as distinguished from the elastic supporter and the invention also includes a particular form of supporter made of such pliable material.

In the accompanying drawings, Figure 1 is a view of an indeterminate length of one form of collar supporter within my invention; Fig. 2 shows another form of the supporter of a length suitable for a single collar; and Figs. 3 and 4 show two different forms of collars as examples of those with which my invention is adapted to be used.

The supporter is made preferably of round wire, but may be made of wire or strips of other cross section. It is furthermore made throughout of one continuous piece of wire and comprises essentially a base length *a* which is at intervals provided with fingers *b*. These fingers may be all of the same length as seen in Fig. 1, or they may be of graduated lengths as shown in Fig. 2, the longest finger being at the middle and the shortest at the two extremities, or vice-versa as may be desired to correspond to the style of collar upon which the supporter is to be used; in fact the length of these fingers may vary in any regular or irregular way. The

fingers are formed by bending the wire into a loop, the sides of which are parallel and in juxtaposition, then twisting the two sides of the loop upon themselves to give the appearance shown in the drawing. This twisting imparts a certain amount of stiffness and body to the fingers and prevents the two sides of the loop from separating, thus making it convenient to construct the supporter as a whole out of a single piece of wire. The wire of which the supporter is made is preferably of a soft, pliable nature so that the fingers can be bent to any curvature or angle to conform to the shape of the collar without returning to their original straight shape. Such a supporter is applied to the collar by securing the base length *a* at or near the neck band of the collar and then bending the individual fingers *b*, so that they will rest against the face of the collar, either inside or outside thereof, and will conform to the shape of the collar at the locations where the respective fingers occur. This is shown clearly in Figs. 3 and 4. The fingers being all connected together by the base length *a* and being of pliable material will preserve the shape of the collar under all ordinary conditions of use.

Since the supporter herein described is made up of a single piece of wire, it is obvious that indeterminate lengths may be made up and containing a number of complete collar supporters which may be separated by simply cutting the base wire *a* at the proper points to obtain the length desired.

Having described my invention, I claim:

1. A collar supporter comprising a single strip of wire-like material comprising a base length and a series of spaced fingers extending therefrom, each finger comprising two parallel lengths of wire twisted together.

2. A collar supporter comprising a base length having a series of integral fingers projecting at intervals therefrom, said fingers being of pliable, but inelastic material.

3. An article of manufacture consisting of a length of inelastic wire having a number of integral fingers projecting therefrom at

intervals sufficient to form a plurality of collar supporters, the device being adapted to be cut up into lengths each including a number of said fingers and each length 5 adapted as a collar supporter, substantially as described.

In witness whereof, I subscribe my signature, in the presence of two witnesses.

CHARLES POULAIN.
